(57) **CLAIM**

The ornamental design for an athletic sandal, as shown and described.

DESCRIPTION

FIG. 1 is a frontal perspective view of a right-foot athletic sandal in accordance with the invention;

FIG. 2 is a front elevation view of the right-foot athletic sandal;

FIG. 3 is a rear elevation view of the right-foot athletic sandal;

FIG. 4 is a left side elevation view of the right-foot athletic sandal;

FIG. 5 is a right side elevation view of the right-foot athletic sandal;

FIG. 6 is top plan view of the right-foot athletic sandal; and, FIG. 7 is a bottom plan view of the right-foot athletic sandal. The broken lines depict a portion of the article and form no part of the claimed design.

1 Claim, 4 Drawing Sheets
